(57) **CLAIM**

The ornamental design for a wrist band data storage device, as shown and described.

DESCRIPTION

FIG. 1 is a perspective view of a clasped wrist band data storage device illustrating the new design;

FIG. 2 is a right side view thereof; where a left side view is not presented, as it is a mirror image of the right side view;

FIG. 3 is a top side view thereof;

FIG. 4 is a bottom side view thereof;

FIG. 5 is a front view thereof;

FIG. 6 is a rear view thereof; and,

FIG. 7 is a perspective view of an unclasped wrist band data storage device illustrating the new design.

In FIG. 7, the broken lines showing a data port of the wrist band data storage device are for illustrative purposes only and form no part of the claimed design.
